UNITED STATES PATENT OFFICE.

FRANK POCOCK, OF SALT LAKE CITY, UTAH.

BEET TOPPER.

Application filed March 11, 1921. Serial No. 451,474.

To all whom it may concern:

Be it known that I, FRANK POCOCK, a citizen of the United States, residing at Salt Lake City, in the county of Salt Lake 5 and State of Utah, have invented certain new and useful Improvements in Beet Toppers, of which the following is a specification.

My invention relates to beet topping machines, and has for its object to provide a machine to engage the foliage of beets which have been loosened in the soil between a pair of traveling chains and by said engagement to convey the beets to a 15 position between two other traveling chains and while the foliage is still held by the first chains the bodies of the beets are individually moved by the adjusting chains to a topping knife and each beet topped at 20 the desired place relative to its top and bottom.

These objects I accomplish with the machine illustrated in the accompanying drawings in which similar letters and numerals 25 of reference indicate like parts throughout the several views, and as described in the specification forming a part of this application, and pointed out in the appended claims.

30 In the drawings in which I have shown a substantial embodiment of my invention, Figure 1 is a plan view of the machine, parts cut away. Figure 2 is a side elevation of the machine, parts cut away. Figure 3 is a vertical section of the bearing for the front end of the adjusting chains. Figure 4 is an edge view and end elevation of one of the links of the adjusting chains. Figure 5 is an edge view and end elevation 35 of one of the links of the elevator chains. Figure 6 is a rear end elevation of the machine, parts omitted and parts cut away. Figure 7 is a plan in detail of the knife moving mechanism.

45 One of the difficulties to be overcome in topping beets has been and is to top each beet at such place relative to the foliage and body as will remove the useless top and none of the body of the beet from which 50 sugar may be made. My invention consists of a machine to be used in connection with a digging element which will loosen the beets in the soil and I then provide two coacting chains which will engage the 55 foliage of the beet and gradually draw it from the ground and convey it, with the

body hanging from said chains, which are of special design, to another pair of coacting chains, which last mentioned chains are also of special design and construction, and 60 which will also engage the foliage at or near the top of the body and contacting with the body will move the beet downwardly while it is being moved by the first 65 mentioned chains toward and to the topping element, which in the present invention is a rotary serrated disk. All of the beets will be topped at a predetermined 70 distance from the bottom of the foliage.

The present invention consists of a rectangular frame A which is mounted on the axle of traction wheels B and the swivel wheels C. The axle D is journaled in each of said 75 wheels B and between each of said wheels and the portion of the said frame A adjacent are operatively carried the spur gears 1. A horizontal shaft 2 is journaled on said frame

A to the rear and above the said axle D, and on said shaft 2 are secured the pinion gears 3, with a portion formed as one part of a clutch, and which pinions each mesh with its respective spur gear 1. The other portion of the clutch is splined on the said shaft 2 in order that the shaft 2 may be operatively 80 connected with said pinion gears 3 and there- 85

by with the traction wheels. A hand lever 41 is provided to operate said clutches. On said shaft 2 are secured the bevel gears 4, the teeth of which mesh with the teeth of bevel pinions 5. The said bevel pinions 5 are each 90 secured on a vertical shaft 6, which shafts 6 are journaled at their lower ends in bearing members E, which are carried on said shaft 2, and at their upper ends the said shafts 6 are journaled in the elevator frames G. In 95 the upper portion of each of said vertical shafts is provided a universal joint F', and the said shafts 6 are also journaled in bearings 40 which are fastened to the vertical portions or legs of a frame or yoke F. Above 100 the said bevel pinions 5 and on each of said shafts 6 is secured a sprocket wheel 7, and between one of the said sprocket wheels 7 and one of said pinion gears 5 is secured a larger sprocket wheel 8. The elevator frames 105 G are fastened at an incline to said frame F and to braces 15 and 29, with the front portion of said elevator frames carried and operated by suitable mechanism which is not new and is not shown but is carried on the 110 front portion of said frame A. The said frame or yoke F is pivoted on said shaft 2

and is given an inverted U-shape. In brackets H which are fastened on said elevator frames G are journalled the short vertical shafts 9, each of which has secured thereon a 5 sprocket wheel 10, and on each of said sprocket wheels 10 and its respective sprocket wheel 7 is operated the endless adjusting chain 11. The elevator frames G each consist of two angle irons 13 fastened together 10 to form an inverted T-shaped member, and a flat bar 34 which is held and spaced from the horizontal portion of said T-shaped member by guide strips and the hub of sprocket wheels 70 which are carried by said 15 frames G. The said T-shaped angle irons 13 are rigidly held in spaced relation to each other by the inverted U-shaped braces 12, this construction allowing the foliage of the beets to pass between said elevator frames. 20 Between said angle irons 13 and the flat bar 34 below them is carried one lead of the elevator chains 16, each of which is made up of links. Spring-held chain-tightener wheels 14 are mounted between the leads of said 25 adjusting chains to cause them to grip the foliage and top of the beets more tightly. The rear portion of said elevator frames G with the supporting yoke or frame F and all of the topping mechanism is pivoted on 30 said shaft 2 in order that the mesh of the gears and chains with their sprockets will remain in mesh and constant. Chain belt tightener wheels 70 of the sprocket type are journalled between the angle irons 13 and 35 the flat bar 34 to regulate the tension of the said chains 16.

As sugar beets are grown in different soils the foliage in some patches of beets will be found rank and the bodies of the beets growing high out of the soil while in other patches the beets grow low in the soil, and in topping the beets grown high in the soil the cut must be somewhat below the crown of the beet as beets grown under those conditions will have foliage covering this crown while with beets grown low in the soil the foliage will be less rank and practically the foliage will not cover much of the crown, and in order to top beets grown under the 50 different conditions I provide two adjusting mechanisms in my topper. The first one is by means of the adjusting chains 11 operated over the sprocket wheels 7 and 10, which chains are to be operated parallel with 55 the ground and at an angle to the elevator chains 16, which are operated in the frames G. The front portions of the said chains 11 are below the medial portions of the said chains 16, as shown in Figure 2. The said 60 chains 11 are made up of links shown in Figure 4. Each link has a beet engaging blade 17 integral with one side of the link, and carrier lugs 18 integral with the opposite side of said link. The chains 16 65 are made up of links and each link has lugs

39 to engage the foliage of the beet, and with carrier lugs 20 on the opposite face of said links to slide between the said channel iron members 13 and the flat bar 34. The second adjusting means are provided by the 70 elements which are shown in the present invention and consist of the movable support 21 each end of which is carried in the braces 29, and each end of said support 21 is moved for adjustment by the frame 23, with the lever 47.

The operation of my topper is as follows:—

The front end of the elevator frame G is lowered until the foliage hooks 24 are near 80 the ground and in front of the digging plow of any of the devices now on the market for digging beets. The two foliage hooks 24 are secured on the front end of said frame G to engage and raise the free end portions of 85 the foliage and direct said foliage between the chains 16, and with the said lugs 39 engaging and gripping the foliage. The digging elements loosen the beets in the ground and the beets are drawn out of the loosened 90 soil by the upward travel of said chains in their respective frames, and said beets are carried by the foliage with their bodies suspended, and when the individual beet is brought between the adjusting chains 11, 95 the foliage will be engaged by the blades 17, and from that time until the beet is topped its foliage will be engaged by both link chains. The lug engagement of the foliage by elevator chain 16 will be the 100 greater, and as the two chains 11 and 16 gradually diverge the beets will be gradually raised and the blades 17 of the lower or adjusting chain 11 will slip in and on the foliage until the end of the said blades 17 will 105 contact with the body of the beet at or near the point where it should be severed, and from that time until the knife is reached, the engagement of the lower chain will be the greater and the slipping of the foliage of 110 the beet will be through the lugs 39, and thereby all beets will be brought to a common topping level and in line with the knife, where the topping will be effected. If all of the beets should have rank foliage the said 115 blades 17 would engage the body of the beet at the bottom of the foliage although some of the beet body will extend above that line and form a crown which has no value as to sugar contents, and with beets having rank 120 foliage there is no danger of the foliage being pulled out of the carrier chains 16 before they are topped, but with beets having less and shorter foliage the topping must take place before the two engagements are 125 broken by the divergence of the chains, and to prevent this the operator must move the topping knife forward which is done by moving the said support 21 forward, and thereby the sprocket wheel 18 and knife 19 will 130

be advanced and top the beet while engaged by both chains. The spring held idler pulleys 30 allow said adjustment of the sprocket chain 31 without interfering with the travel 5 of the chain 31, or the movement of the knife 19. The two coacting chains 11 begin to diverge in their line of travel a short distance behind the topping point and the foliage will be carried up and released from 10 the upper end of the elevator chains and may be directed to one side of the machine, while the topped beets will fall in a row, or be held in suitable receptacles and dumped in piles.

15 I thus provide new and novel elevator chains having foliage engaging lugs which will engage the foliage but not to the extent of preventing the foliage from being slipped between said chains, and with new and novel 20 adjusting means to engage the body of the beet and thereby slip the foliage between the elevator chains and bring all of the beets to a common horizontal plane and in alignment with the topping knife, said adjusting 25 means consisting of coacting chains with new and novel engaging blades on each link thereof, and with new means of moving said knife along the horizontal travel of the beets.

30 Having thus described my invention and its operation I desire to secure by Letters Patent and claim:—

1. In a beet topper the combination with traction wheels, of a frame having one end 35 thereof supported by said wheels; a shaft rotatable by said wheels; an elevator frame pivoted at one end on said shaft; elevator chains carried in said elevator frame and each chain consisting of links; lug pins integral with each of said links to engage the foliage of the beets; an inverted U-shaped frame pivoted on and supported by said shaft; vertical shafts journaled at their lower ends in bearing supports carried on 40 the first mentioned shaft, and other bearings for said shafts carried on said U-shaped frame; gears to impart motion from said first mentioned shaft to said vertical shafts; sprocket wheels on said vertical shafts; other 45 sprocket wheels journaled on said elevator frame; horizontally operated sprocket chains carried on said sprocket wheels, and each chain consisting of links having integral blades thereon to engage the bodies 50 of beets carried by said elevator chains; and

a horizontally movable topping knife mounted for rotation below said horizontally operated chains.

2. A beet topper comprising an inclined elevator frame; coacting elevator chains 60 carried in said frame; lugs on each of said chains to engage the foliage of beets and thereby move the beets up said inclined elevator; a pair of coacting adjusting chains 65 horizontally disposed and operated, each chain consisting of links having integral blades thereon to engage the bodies of the beets as they are moved by said inclined chains to bring the beets to a common level; and means to top said beets as they are 70 moved horizontally by said last mentioned chains.

3. A beet topping machine comprising two coacting adjusting chains operable over sprocket wheels, each chain consisting of 75 links having carrier lugs on one face to engage the rims of said sprocket wheels and tightener wheels, and transverse blades on the other face to engage the foliage and bodies of the beets. 80

4. A beet topping machine comprising coacting elevator frames, each frame consisting of spaced apart angle irons, and a flat bar below and spaced from said angle irons; inverted U-shaped braces having the leg 85 portions fastened between said angle irons; sprocket wheels mounted in said frames; sprocket chains operable over said wheels, each of said chains consisting of links having lugs extended from one face and carrier 90 lugs extending from the other face.

5. A beet topping machine comprising coacting elevator chains operable on inclined frames, each of said chains consisting of links having lugs extending from one face 95 of the link and carrier lugs on the other face; adjusting chains operable horizontally over sprocket wheels below said elevator chains one of which sprocket wheels is journaled in close proximity to the underside 100 of said elevator chains; and each of said adjusting chains consisting of links each having foliage engaging blades extended from one face and carrier lugs on the other face; with means to move said chains longitudinally; and a topping knife adjacent said 105 adjusting chains.

In testimony whereof I have affixed my signature.

FRANK POCOCK.
